[57] CLAIM

The ornamental design for a vehicle running board, as shown and described.

DESCRIPTION

FIG. 1 is a top, end perspective view of a vehicle running board showing my new design;

FIG. 2 is a front elevation view thereof on a reduced scale broken away in the middle for convenience of illustration;

FIG. 3 is a top plan view of FIG. 2;

FIG. 4 is a bottom plan view of FIG. 2;

FIG. 5 is a rear elevation view of FIG. 2; and,

FIG. 6 is an end elevation view thereof, the opposite end being a mirror image of that shown.

FIG. 1

FIG. 3

FIG. 2

FIG. 4

FIG. 6
